DISTRIBUTOR FOR IGNITION SYSTEM

Wytze Beye Smits, Voorburg, Netherlands, assignor to Smitsvink, N. V., Leidschendam, Netherlands, a company

Application June 22, 1954, Serial No. 438,487

3 Claims. (Cl. 200—24)

This invention relates to a distributor, and more particularly to a distributor specifically designed for use with an ignition system employing low voltage spark plugs operating on condenser discharges.

Some of the problems connected with the operation of distributors which have been used heretofore are pointed out in the inventor's Patent No. 2,587,780 issued March 4, 1952, for "Electrical Ignition System." In that patent a distributor is described which is provided with a plurality of outer fixed contacts and an inner rotating contact. It can be readily appreciated that both the rotating contact and fixed contacts tend to wear away and as they wear away, the timing of the ignition system is delayed. The width of the contacts determines the length of time the contacts may be used without replacement, but it is also true that the wider the contacts, the greater the timing may be delayed. Accordingly, one of the problems in connection with the use of prior art distributors has been to strike a balance as to the width of the contacts so as to permit relatively infrequent replacement and yet not produce too large a time delay.

Another of the difficulties encountered in prior art distributors relates to the heat produced by the sparking between the rotating contact and the fixed contacts. It can be seen that in the rotating contact a great deal more heat is produced than in the fixed contacts, since sparks are created on the rotating contact many times more than on individual fixed contacts. The heat created by this sparking is not easily dissipated and consequently, the gap between the rotating and fixed contacts is not maintained at the correct dimensions.

In addition, it has been customary to support the rotating contact arm on a spindle between two spaced bearings and it has frequently occurred that these bearings become slightly displaced and the gap between the rotating and fixed contacts is varied.

The present invention seeks to overcome all of the foregoing disadvantages of prior art distributors and yet provides a distributor which is practical, relatively inexpensive to manufacture and of simple construction. A plurality of fixed contacts are provided on an inner insulated block, and these fixed contacts are connected with respective spark plugs. An arm is provided which rotates on an elongated sleeve disposed on a central spindle. This arm is provided with a contact which engages the fixed contacts as the arm rotates about the spindle. A condenser is connected with the contact on the rotating arm and the condenser is charged during the time the rotating contact is traveling between the fixed contacts and discharges when the rotating contact is sufficiently close to a fixed contact for the charge to jump the gap and discharge across the spark plug.

The distributor described herein is intended for use primarily with low voltage spark plugs such as disclosed in the inventor's Patent No. 2,125,035 issued July 26, 1938 for "Electric Ignition System and Sparking Plug for Internal Combustion Engines." The essential feature of such spark plugs is that they employ relatively low volt-

ages and provide a spark which in effect creeps across the surface of the plug. This creeping discharge is attained by providing a semi-conductor between the electrodes of the plug. One of the principal advantages of such spark plugs is that they are capable of operating on a condenser discharge and that a distributor can be used to sequentially connect the ignition condenser with individual spark plugs.

By virtue of the novel arrangement of parts of the presently described distributor, more exact timing is possible with the same width of contacts as is used in prior art distributors. This is occasioned by the fact that the radius of the rotating contact arm is greater and, consequently, the angle through which the rotating contact arm moves from the initial sparking position to the sparking position when the contact members are worn down is correspondingly smaller. As is pointed out in the inventor's Patent No. 2,587,780, previously referred to, it is this angle which determines the possible variation in the timing. In this manner, inventor has decreased the variation in timing without affecting the life of the contact points.

The present invention also permits the rotating contact arm to be better cooled so that the heat created by sparking does not expand the metal contact member and vary the size of the spark gap. The rotating arm is more efficiently cooled since it is traveling at a larger linear velocity and since it is mounted on the outside of the rest of the distributor parts and receives a greater circulation of air.

The rotating arm of the presently described distributor is supported in bearings along its entire length to insure that the correct sparking distance is maintained between the fixed contacts and the rotating contact at all times.

The present invention provides a distributor which, if desired, may be provided with wider contacts and correspondingly increased life without any sacrifice in the exactness of timing over the prior art distributors. This may be accomplished by reason of the fact that the radius of the rotating arm is greater and the angle between the initial sparking point and the sparking position when the contacts are worn down is substantially smaller. Thus, it is possible to widen the contacts and bring the above referred-to angle to the same value as with prior art distributors. In this manner, the distributor may be used for a longer period of time without replacing the contacts.

A primary object of this invention is to provide a distributor which gives greater exactness in timing with no sacrifice in the life of the distributor.

A further object of this invention is to provide a distributor in which the gap between the fixed contacts and the rotating contact is more accurately maintained at the correct dimension.

Other objects and many of the attendant advantages of this invention will become apparent in the light of this specification when considered in connection with the accompanying drawing wherein:

Fig. 1 is a diagrammatic plan view of a distributor constructed in accordance with the present invention and

Fig. 2 is a sectional view of the distributor shown in Fig. 1.

In the drawings, 1 is a rotor spindle, the upper end of which is provided with a contact 1a connected to a condenser 2 which is suitably grounded. Secured to the rotor spindle 1 in any suitable manner is a U-shaped member having outwardly extending arms 3 and 5. Suitably secured on the outer end of arm 3 is a contact 4, and mounted on the outer end of arm 5 is a weight 6 which counter-balances the weight of the contact 4.

An insulating block 7 which is fixed with respect to the rotatable U-shaped arm is provided with a plurality of equidistantly spaced stationary contacts 8. These contact members are connected with individual spark plugs 9 as clearly shown in Fig. 1.

The presently described distributor operates in the following manner. The rotor spindle 1 rotates and rotates the U-shaped arm and contact 4 about the insulating block 7 provided with the stationary contacts. The condenser 2 is charged by a circuit (not shown) during the period of time that the rotating arm is traveling between contacts 8. When contact 4 approaches a stationary contact 8 the charge on condenser 2 will discharge through a spark plug 9. By providing the rotating arm on the outside of the fixed contacts, the radius of the rotating arm is increased and more exact timing is attained. Furthermore, since the rotor spindle is supported throughout its length in insulating block 7, the maintenance of the proper spark gap dimensions between rotating contact 4 and the stationary contacts is assured.

Obviously, many modifications and variations of the present invention may be employed without departing from the essentials thereof. What is claimed as new and desired to be secured by Letters Patent is:

1. In a distributor to distribute a point to point spark in a low voltage ignition system, a rotatable spindle, an insulating block journaled on said spindle, a plurality of stationary contacts fixed in said insulating block, an angular arm mounted on said spindle and having a portion ex-

tending adjacent the outer periphery of said insulating block, and a contact member of substantially the same width as said stationary contacts mounted on said arm

for rotation therewith and for cooperation with said stationary contacts, said contact member being spaced from

said stationary contacts by predetermined spark gap.

2. A distributor according to claim 1 wherein a second angular arm having a counterweight mounted thereon is attached to said spindle diametrically opposite said first angular arm.

3. In a distributor according to claim 2, wherein said angular arms are attached to said spindle below the insulating block.
